PUMP PISTON PACKING

William Toward, Poland Mines, Pa.

Application August 20, 1935, Serial No. 37,048

1 Claim. (Cl. 309—29)

My invention relates to packing, and while primarily intended for pistons of liquid pumping apparatus, it will be obvious that the packing may be employed in connection with pistons of various types of fluid pumping and compressing mechanisms wherein it is found to be applicable.

Important objects of the invention are to provide a packing of the character described, which is constructed of wood, which embodies separate sections and novel means for maintaining the latter in constant operating engagement with the wall of the associated cylinder, which is extremely durable and highly efficient in its use, and economical in its manufacture, installation and operation.

With the foregoing and other objects in view which will appear as the description proceeds, the invention consists of the novel construction, combination, and arrangement of parts herein specifically described and illustrated in the accompanying drawing, but it is to be understood that the latter is merely illustrative of an embodiment of the invention, and that changes in the form, proportions, and details of construction may be resorted to that come within the scope of the claim hereunto appended.

In the drawing wherein like numerals of reference designate corresponding parts throughout the several views:

30 Figure 1 is a side elevational view, partly in cross section, of a pump piston embodying the present invention.

Figure 2 is an end view of one of the packing ring sections, and Figure 3 is an end view, partly in cross section, of the assembled packing ring sections.

Figures 4 and 5 are inner views of packing ring sections.

Referring in detail to the drawing 1 denotes a piston-rod of an ordinary form and construction including a reduced end portion 2, which latter extends through the diametric center of a piston-head 3 and through a cylindrical spacing sleeve 4 preferably formed integral with the said piston-head.

The reduced end portion 2, of the piston-rod 1, further extends through the diametric center of an annular follower 5, which is fitted against the free end of the spacing sleeve 4 and secured in place by a nut 6 engaged on the threaded extremity of said reduced end portion 2.

My improved piston packing comprises a pair of packing rings, respectively indicated at 7 and 8, which may be constructed of any suitable wood material, preferably and particularly gum-wood,

as the latter is not grainless and has been proven, by extensive tests and experiments, to be insusceptible to fracture, and extremely durable and efficient for packing purposes for pump pistons.

The packing ring 7 consists of two separate, complementary, semi-circular sections, respectively indicated at 9 and 10, and the packing ring 8 consists of similar sections, respectively indicated at 11 and 12. The packing rings surround the spacing sleeve 4, with the ring 7 disposed adjacent to the piston-head 3, and with the ring 8 disposed adjacent to the follower 5. The rings have their opposed or adjacent faces positioned flatly against each other, and are not fixedly clamped in place between the piston-head and the follower, as the distance between these latter elements is determined by the length of the interposed spacing sleeve, and is such as to provide sufficient clearance to allow the free movement of the packing rings with respect to their connection with the piston structure.

Each end of each of the ring sections 9, 10, 11, and 12, is provided with a pocket 13 for the reception of an expander 14, which is preferably in the form of a coil spring, as shown in Figure 1, or in the form of a rubber plug 15, as illustrated in Figure 3. An expander is carried in the pockets 13 between the contiguous ends of each associated pair of ring sections, and are of sufficient power to force the latter outwardly to provide the required operative engagement of the peripheral faces of the packing rings with the wall of the associated cylinder bore to effect the most efficient operation.

To minimize the possibility of leakage, the packing rings 7 and 8 are arranged so that the break between the ends of sections 9 and 10 will be disposed at right angles relatively to the break between the ends of the other pair sections 11 and 12. To maintain this relative position of the rings with respect to each other, a dowel pin 16 is fixed in the section 9, of the ring 7, and projects into an open slot 17 formed in the inner periphery of the section 11 of the ring 8.

The inner edge margin of that face, of the ring 7, disposed towards the piston-head 3, and the inner edge margin of that face, of the ring 8, disposed towards the follower 5, are recessed, as at 18, to necessitate machining only the adjacent peripheral edge margins of the piston-head and follower, respectively, to provide an accurately flat and uniform engagement of the rings with the piston-head and follower during the reciprocation movement of the piston in the associated cylinder.

To install the packing rings 7 and 8, the nut 6 and follower 5 are removed from the piston rod reduced end portion 2. The ring sections 9 and 10, constituting the ring 7, assembled with the expanders 14 between the ends thereof, are forced into the cylinder against the piston-head 3. The ring sections 11 and 12, constituting the ring 8, are then assembled with their expanders and forced into the cylinder against the installed 10 ring 7 to complete the packing operation after the follower and nut have been replaced. The provision of the open slot 17 in the ring section 11 renders it comparatively easy to locate the dowel pin 16 in the ring section 9, as said dowel 15 pin is visible through the slot. The engagement of the dowel pin in said slot assures the proper relative positions of the packing rings 7 and 8 with respect to each other to position the breaks 20 between the ends of the sections of one ring at right angles to the breaks between the ends of the sections of the other ring.

The non-recessed face of the ring 7, and the recessed face of the ring 8, are each preferably formed with two pairs of sockets 19, which are disposed on respective sides of and adjacent to the breaks thereof. Each pair of adjacent sockets are adapted for the engagement by a suitable tool capable of forcing and holding each pair 30 of associated ring sections toward each other against the action of the expanders 14 to facilitate the installation of the packing rings 7 and 8 into the associated cylinder in the manner set forth.

35 While the present invention is herein illus-

trated and described as embodying two packing rings, it is obvious that the number of rings may be varied to best meet conditions found in practice. Further, any other suitable type of expander capable of forcing the ring sections outwardly against the wall of the cylinder bore may be used instead of the forms thereof, indicated at 14 and 15.

The present invention provides a most efficient packing for the pistons of pumps and the like, 10 which will outwear any other types of packing for such purposes now in use, and which may be economically constructed, installed, and replaced.

What I claim is:

In a piston for a pump cylinder, the combination of a pair of packing rings constructed of wood and positioned flatly against each other on said piston, each of said packing rings comprising a pair of separate semi-circular sections, 20 the breaks between the ends of one of said pair of sections being disposed at right angles with respect to the breaks between the ends of the other of said pair of sections, means carried by each of said pair of sections for expanding the 25 latter, means fixed in one of said pair of packing rings and engaging in a slot in the other of said pair of packing rings for maintaining the relative positions of said pair of packing rings on the piston, and means formed in each of said pair 30 of sections engageable to hold the latter in contracted position, the inner edge margin of one face of each of said pair of packing rings being recessed.
